CLAIM

The ornamental design for an electrical extension cord, as shown and described.

DESCRIPTION

FIG. 1 is a perspective view of a first embodiment of an electrical extension cord showing our new design;

FIG. 2 is a left side elevation thereof;

FIG. 3 is a front elevation thereof;

FIG. 4 is a right side elevation thereof;

FIG. 5 is a rear elevation thereof;

FIG. 6 is a perspective view of a second embodiment of an electrical extension cord showing our new design;

FIG. 7 is a left side elevation thereof;

FIG. 8 is a front elevation thereof;

FIG. 9 is a right side elevation thereof; and,

FIG. 10 is a rear elevation thereof.

The broken lines in the drawings are for the purpose of illustrating portions of the electrical extension cord that form no part of the claimed design.
